UNITED STATES PATENT OFFICE.

DOSSA DIXON EVINS, OF DAVENPORT, IOWA, ASSIGNOR OF ONE-HALF TO FRANK W. ELLIOTT, OF DAVENPORT, IOWA.

POSTURE-ADJUSTING TABLE.

Application filed November 28, 1924. Serial No. 752,509.

To all whom it may concern:

Be it known that I, DOSSA D. EVINS, a citizen of the United States, residing at Davenport, in the county of Scott and State of Iowa, have invented a certain new and useful Improvement in a Posture-Adjusting Table, of which the following is a specification.

My invention relates to an operating table or posture-adjusting table and has for one purpose the provision of a posture-adjusting table for use in chiropractic or osteopathy or any other methods of treatment where pressure is applied to the back or spine of the patient. One object of my invention is to provide an adjusting table upon which a patient can easily take a comfortable initial position, and which may then be moved, without effort by or discomfort of the patient to the final operating posture.

Another purpose is to provide a table of the class described in which the posture of the patient may be altered or adjusted mechanically without intervention of the patient.

Another purpose is the provision of a table of the class described which is usable with and adjustable to patients of different heights. Other objects will appear in the course of the specifications and claims. I illustrate my invention more or less diagrammatically in the accompanying drawings wherein:

Fig. 1 is a perspective view of my device in the initial position.

Fig. 2 is a side elevation of the same mechanism in operating position.

Fig. 3 is a side elevation of the same mechanism in an intermediate position.

Fig. 4 is a side elevation of the same mechanism in the initial position.

Fig. 5 is a detailed, longitudinal, sectional view.

Fig. 6 is a side elevation of a modified or variant form of my device in which springs are used to provide the motive power, and

Fig. 7 is a detail on an enlarged scale of the structure of Fig. 6.

Like parts are indicated by like symbols throughout the specifications and drawings.

A is the base frame work comprising the opposite pairs of supporting feet A¹ and A²

and supporting plate A³ to which is secured a housing A⁴ and any suitable electric motor A⁵. Upwardly extending from the frame A and above the legs A² are the supporting arms A⁶.

Pivoted as at B¹ to the tops of the arms A⁶ is a supporting frame comprising the side elements B, lower transverse element B², and the intermediate transverse element B³.

Pivoted to the arms A⁶ as at C, adjacent their junction with the frame A, are the links C¹ the outer ends of which are pivoted as at C² to the table-supporting elements C³ the upper ends of which are pivoted to the side elements B as at C⁴. The elements C³ are upwardly and outwardly bent as at C⁵ and continue as the horizontal supporting portions C⁶.

Pivoted to the tops of the side elements C as at D is a supporting yoke D¹ the outer end of which terminates in the flat surfaced bearing lug D², and the inner end of which is pivoted as at D³ to links D⁴ the opposite ends of which are pivoted as at D⁵ to the members C³.

Secured upon the yoke D is the upper operating pad of the table element E, from the forward end of which depends the slotted adjusting leaf E¹, pivoted at its inner end as at E², and adapted to be penetrated, along its outer slotted end, by the bolt E³ and to be engaged by the adjusting nut E⁴ screw-threaded thereabout, which clamps the slotted leaf E¹ against the opposed bearing lug D². Pivoted to the opposite end of the element E as at E⁵ are the adjusting leaves E⁶, slotted as at E⁷, and adapted to engage the opposed flat surfaces of the opposite end of the yoke D¹. E⁸ are bolts mounted on said yoke and penetrating the slots E⁷, and E⁹ are any suitable clamping means. E¹⁰ are hand holds secured to the element E at each side thereof.

The outward extensions C⁶ of the elements C³ form tracks upon which ride the table frame side elements G which are joined by the transverse element G¹, and are provided with the wheel-supporting lugs G² G³ on which are mounted the slotted or flanged wheels G⁴ G⁵ engaging the upper and lower edges of the extensions C⁶. The outer ends of the elements C⁶ are joined by a yoke

G^{10} secured for example by the bolts G^{11} and nuts G^{12} to the outwardly projecting ears G^{13} .

Rotatable in the ear on lug G^{14} in the center of said yoke G^{10} is the adjusting worm H which is in screw-threaded relation with the lug H^1 downwardly depending from the transverse element G^1 . The opposite end of the worm H rotates in the bearing H^2 , as shown in Fig. 5, and is provided with a bevel gear H^3 in mesh with the bevel gear H^4 on the rotating shaft H^5 which rotates within the combined shield and bearing element H^6 which in turn is bolted at each end to the element C^3 by means of the outwardly projecting arms H^7 H^8 . The opposite end of the shaft H^5 terminates in a bevel gear H^{10} in mesh with the bevel gear H^{11} controlled by the shaft H^{12} of the manual cranks H^{13} .

The housing A^4 contains any suitable mechanism, the details of which form no part of the present invention, it being understood, however, that in response to pressure upon the foot pedal K the crank K^1 , in response to the action of the motor A^5 or any other suitable motive power, will make a half revolution and stop at the end of such half revolution. Each crank K^1 is pivoted at its outer end as at K^2 to a link K^3 , the opposite end of which is pivoted as at K^4 to the side of element B .

In Figs. 6 and 7 I illustrate a somewhat modified form of my device wherein powerful springs L , as substitutes for the motor elsewhere shown, provide the motive power for lifting the table into elevated position. Each spring L is secured at one end as at L^1 to the frame A and is at its opposite end secured to the extension L^2 of the side element B , the extension L^2 being made of sufficient length to give sufficient leverage to permit the springs, when released, to lift the table to raised position. In Fig. 7 I illustrate more or less diagrammatically a tensional adjustment for the springs, comprising the eyelet L^3 to which the spring is secured, the pin L^4 about which the eyelet may rotate, the screw L^5 and the knurled thumb piece L^6 .

It will be realized that, while I have illustrated an operative device, obviously many changes may be made in the size, shape, number and disposition and relation of parts without departing from the spirit of my invention. Therefore, I wish my description and drawings to be taken as in a broad sense illustrative rather than as limiting me to the specific mechanism herein described and shown.

The use and operation of my invention are as follows:

In giving therapeutic treatments, such as in chiropractic and osteopathy, wherein the patient is subjected to manual pressure or

manipulation along the spine, it becomes desirable to provide an adjusting table or couch which is as comfortable as possible for the patient and as convenient as possible for the doctor, and which permits of ready adjustment to suit the size of the patient and to bring the body of the patient into the posture best suited for the particular treatment being given.

I provide an adjusting table having two body supporting portions, namely, a lower upholstered pad upon which the patient may kneel and which thus supports the lower portion of the body, and an upper pad to support the upper portion of the patient's body. In order to reduce to a minimum the difficulty or discomfort attendant on positioning the patient on the table, I employ a moving supporting mechanism for the two pads, which holds the pads in an initial position adapted for the easy mounting of the patient upon the table and which can subsequently move the two pads, and the patient upon them, to the proper adjusting or operating position.

The lower of the two pads is of such height that the patient can easily kneel upon it. The upper pad, in its preliminary position, substantially higher above the base than the lower pad and lies in a plane almost at right angles to the plane of the lower pad. I provide sideholds or hand bars which the patient may grasp with his hands in order to steady himself for the downward trip of the mechanism. The patient then leans against the upper pad, resting his chest against it and turning his head sideways. At the instruction of the doctor he moves his hands along the side bars until his chest is properly positioned along the supporting pad, this adjustment being completed or corrected after the two pads have been moved into the operating position. The doctor then actuates the necessary mechanism and the electric motor or other motive means moves the pivoted main supporting frame downwardly toward the base. This movement of the main supporting frame has the effect of moving the knee engaging pad somewhat away from the base and into a lower position without, however, tilting it from its relatively horizontal plane. The upper pad on the contrary tilts and folds downwardly until it reaches a level substantially lower than its original level and lies in a substantially horizontal plane as shown in Figure 2. In order to obtain correct posture the doctor can then instruct the patient to move his hands along the handholds, thus adjusting the position of his head and chest upon the upper pad.

Also by turning one of the hand cranks provided, the doctor can longitudinally move the knee supporting pad and thus adjust the position of the patient without effort or dis-

comfort to the patient himself. The upper pad is provided with vertical adjusting leaves at both its front and rear and thus its angular relation to the supporting element upon which it is mounted can be adjusted to suit the needs of any particular patient. When the treatment is completed, the doctor again actuates the mechanism and the table returns to its initial position, lifting the forward part of the patient to an almost erect position, and the patient can then easily step off the table. While I have shown a mechanism in which an electric motor is used, obviously any other motive means might be employed, and the mechanical motor means might even be dispensed with.

I claim:

1. In an adjusting table, a base, a main supporting member pivoted thereto, a body supporting element pivoted at one point on said main supporting member, a second body supporting element pivoted at another point upon said main supporting member and

means for tilting and depressing said first mentioned body supporting element in response to rotation of said main supporting member, and means for maintaining said second body supporting elements in substantially horizontal position during the rotation of said main supporting member.

2. In an adjusting table, a base, a supporting structure mounted thereupon, a pair of body supporting elements mounted at different levels upon said supporting structure, means for moving said two body supporting elements in unison from a predetermined initial position adapted for easy access by the patient, to a predetermined operating position, means for tilting the upper of said body supporting elements, during said movement, from an inclined position to a relatively horizontal position, and means for maintaining the lower body supporting element in a substantially horizontal position throughout the tilting movement of said upper body supporting element.

3. In an adjusting table, a base, a main supporting member pivoted thereto, a body supporting element pivoted adjacent the top of said main supporting member, a body supporting element pivoted intermediate the ends of said main supporting member, and a link connection between said body supporting elements whereby a rotation of said main supporting member rotates said body supporting elements through arcs of different degree.

4. In an adjusting table, a base, a main supporting member pivoted thereto at one end thereof, a body supporting element pivoted adjacent the top of said main supporting member, and adapted to overlie said supporting member and the end of the base to which it is pivoted, a second body sup-

porting element pivoted to said main supporting member intermediate its ends and projecting outwardly and downwardly along the base at a level substantially below that of said first mentioned element, a link connection between said two body supporting elements and a link connection between the lower of said body supporting elements and the base, whereby a rotation of said main supporting member rotates said body supporting elements through arcs of different degree.

5. In an adjusting table, a base, a main supporting member pivoted thereto at one end thereof, a body supporting element pivoted adjacent the top of said main supporting member, and adapted to overlie said supporting member and the end of the base to which it is pivoted, a second body supporting element pivoted to said main supporting member intermediate its ends and projecting outwardly and downwardly along the base at a level substantially below that of said first mentioned element, a link connection between said two body supporting elements and a link connection between the lower of said body supporting elements and the base, whereby a rotation of said main supporting member rotates said body supporting elements through arcs of different degree, and body engaging pads adjustably mounted on each of said body supporting elements.

6. In an adjusting table, a base, a main supporting member pivoted thereto at one end thereof, a body supporting element pivoted adjacent the top of said main supporting member, and adapted to overlie said supporting member and the end of the base to which it is pivoted, a second body supporting element pivoted to said main supporting member intermediate its ends and projecting outwardly and downwardly along the base at a level substantially below that of said first mentioned element, a link connection between said two body supporting elements and a link connection between the lower of said body supporting elements and the base, whereby a rotation of said main supporting member rotates said body supporting elements through arcs of different degree, and body engaging pads adjustably mounted on each of said body supporting elements one of said pads being longitudinally adjustable upon the lower of said body supporting elements, and the other being vertically adjustable upon the upper of said body supporting elements.

7. In an adjusting table, a base, a body supporting element and means for supporting it above said base, a second body supporting element and means for supporting it above said base at a substantially higher level, than said first mentioned element in an inclined position, and means for simultaneously tilting said element into a plane.

approximating the horizontal and for moving it downwardly toward said base and body engaging pads mounted on each of said body supporting elements, the pad mounted upon the upper of said body supporting elements being vertically adjustable in relation thereto.

8. In an adjusting table, a base, a body supporting element, and means for supporting it above said base, a second body supporting element, and means for supporting it above said base at a substantially higher level, than said first mentioned element in an inclined position, and means for simultaneously tilting said element into a plane approximating the horizontal, and for moving it downwardly toward said base, body engaging pads mounted on each of said body supporting elements, and independent vertical adjusting means positioned at each end of the pad mounted upon the upper of said supporting elements.

9. In an adjusting table, a base, a body supporting element and means for supporting it above said base, a second body supporting element and means for supporting it above said base at a substantially higher level, than said first mentioned element in an inclined position, and means for simultaneously tilting said element into a plane approximating the horizontal and for moving it downwardly toward said base, body engaging pads mounted upon said body supporting elements, and means for longitudinally adjusting one of said pads along the lower of said body supporting elements.

10. In an adjusting table, a base, a body supporting element and means for supporting it above said base, a second body supporting element and means for supporting it above said base at a substantially higher level, than said first mentioned element in an inclined position, and means for simultaneously tilting said element into a plane approximating the horizontal and for moving it downwardly toward said base, body engaging pads mounted upon said body supporting elements, and means for longitudinally adjusting one of said pads along the lower of said body supporting elements comprising a worm longitudinally disposed along said body supporting element and in mesh with said pad, and means for rotating it.

11. In an adjusting table, a base, a supporting structure mounted thereupon, a pair of body supporting elements mounted at different levels upon said supporting structure, means for moving said two body supporting elements in unison from a predetermined initial position adapted for easy access by the patient, to a predetermined operating position, means for tilting the upper of said body supporting elements, during said movement, from an inclined position to a relatively horizontal position, and means for maintaining the lower body supporting element in a substantially horizontal position throughout the tilting movement of said upper body supporting element, and means for longitudinally adjusting said lower of said body supporting

a relatively horizontal position, and means for maintaining the lower body supporting element in substantially horizontal position throughout the tilting movement of said upper body supporting element, and hand holds positioned along the sides of said upper body supporting element.

12. In an adjusting table, a base, a supporting structure mounted thereupon, a pair of body supporting elements mounted at different levels upon said supporting structure, means for moving said two body supporting elements in unison from a predetermined initial position adapted for easy access by the patient, to a predetermined operating position, means for tilting the upper of said body supporting elements, during said movement, from an inclined position to a relatively horizontal position, and means for maintaining the lower body supporting element in a substantially horizontal position throughout the tilting movement of said upper body supporting element, and hand holds positioned along the sides of said upper body supporting element.

13. In an adjusting table, a base, a supporting structure mounted thereupon, a pair of body supporting elements mounted at different levels upon said supporting structure, means for moving said two body supporting elements in unison from a predetermined initial position adapted for easy access by the patient, to a predetermined operating position, means for tilting the upper of said body supporting elements, during said movement, from an inclined position to a relatively horizontal position, and means for maintaining the lower body supporting element in a substantially horizontal position throughout the tilting movement of said upper body supporting element, and hand holds positioned along the sides of said upper body supporting element.

14. In an adjusting table, a base, a supporting structure mounted thereupon, a pair of body supporting elements mounted at different levels upon said supporting structure, means for moving said two body supporting elements in unison from a predetermined initial position adapted for easy access by the patient, to a predetermined operating position, means for tilting the upper of said body supporting elements, during said movement, from an inclined position to a relatively horizontal position, and means for maintaining the lower body supporting element in a substantially horizontal position throughout the tilting movement of said upper body supporting element, and means for longitudinally adjusting said lower of said body supporting

elements while the patient is positioned thereupon comprising a worm in mesh with said body supporting element, supporting track members upon which said body supporting element is mounted, and means for rotating said worm.

15. In an adjusting table, a supporting base, a main supporting lever pivoted thereto and means for rotating said lever about its pivot, and a pair of body supporting elements pivotally secured to said lever at different points therealong and adapted at all positions of said lever, to be positioned at substantially different heights above the base.

16. In an adjusting table, a supporting base, a main supporting lever pivoted thereto and means for rotating said lever about its pivot, and a pair of body supporting elements pivotally secured to said lever at different points therealong and adapted at all positions of said lever to be positioned at substantially different heights above the base, and body engaging pads, mounted on said elements, and adjustable in relation thereto.

17. In an adjusting table, a supporting base, a main supporting lever pivoted thereon and means for rotating it, a body supporting member pivoted adjacent the outer end of said lever, a second body supporting member pivoted intermediate the ends of said lever, said first mentioned body supporting member being positioned substantially higher above the base than the second member, at all positions of said main supporting lever.

18. In an adjusting table, a supporting base, a main supporting lever pivoted thereon and means for rotating it, a body supporting member pivoted adjacent the outer end of said lever, a second body supporting member pivoted intermediate the ends of said lever, said first mentioned body supporting member being positioned substantially higher above the base than the second member, at all positions of said main sup-

porting lever, and means for rotating said first mentioned member in reponse to rotation of said supporting lever.

19. In an adjusting table, a supporting base, a main supporting lever pivoted thereon and means for rotating it, a body supporting member pivoted adjacent the outer end of said lever, a second body supporting member pivoted intermediate the ends of said lever, said first mentioned body supporting member being positioned substantially higher above the base than the second member, at all positions of said main supporting lever, and means for rotating said first mentioned member in reponse to rotation of said supporting lever, whereby said member is supported in inclined position when said lever is at the upper limit of its excursion and in substantially horizontal position when the lever is at the lower limit of its excursion.

20. In an adjusting table, a supporting base, a main supporting lever pivoted thereon and means for rotating it, a plurality of body supporting members rotatably mounted on said lever and means for rotating said body supporting members in response to rotation of said lever through arcs of substantially different degree.

21. In an adjusting table, a supporting base, a main supporting lever pivoted thereon and means for rotating it, a body supporting member pivoted adjacent the outer end of said lever, a second body supporting member pivoted intermediate the ends of said lever, said first mentioned body supporting member being positioned substantially higher above the base than the second member, at all positions of said main supporting lever.

Signed at Davenport county of Scott and State of Iowa, this 25th day of November 1924.

DOSSA DIXON EVINS.
